UNITED STATES PATENT OFFICE.

JAMES C. ELLISON, OF PHILADELPHIA, PENNSYLVANIA, ASSIGNOR TO
EDWARD A. GREENE, OF SAME PLACE.

IMPROVEMENT IN LOOMS FOR WEAVING PILE-FABRICS.

Specification forming part of Letters Patent No. **222,477**, dated December 9, 1879; application filed July 3, 1879.

To all whom it may concern:

Be it known that I, JAMES C. ELLISON, of Philadelphia, Pennsylvania, have invented a new and useful Improvement in Looms for Weaving Pile-Fabrics, of which the following is a specification.

My invention relates to certain improvements in looms for weaving pile-fabrics, the principal object of my invention being to so construct the thread-catching devices as to insure the proper formation of the loops at all times, and thus prevent breaks in the piled surface. This object I attain in the following manner, reference being had to the accompanying drawings, in which—

Figure 1, Sheet 1, is a side view of a loom with my improvements; Fig. 2, the same with the parts in a different position; Fig. 3, Sheet 2, an end view; Fig. 4, a sectional plan on the line 1 2, Fig. 3; Figs. 5 and 6, Sheet 1, detached views of parts of the loom; Figs. 7, 8, 9, and 10, Sheet 2, diagrams illustrating the formation of the loops; and Figs. 11, 12, and 13, Sheet 3, detached views, drawn to an enlarged scale, of the loop-forming devices.

A represents the breast-beam of a loom, and B the lay, carrying the reed D. To the beam A, at each end of the same, and outside of the line of warp, is secured a box, E, and in each of these boxes slides a bar, a, the outer end of which carries a spring-pin, a', which, under the circumstances described hereinafter, engages with a hook, c, on the lay B, so that as the latter swings the bar is caused to reciprocate longitudinally in the box E.

From the under side of the bar a projects a pin, b, Fig. 5, this pin being adapted to a slot in a plate, d, which forms the bottom of the box, the slot being inclined at the front end, as shown, so that as the bar approaches or recedes from the limit of its forward movement a lateral vibration is imparted to the bar and to the parts carried thereby.

Each bar a carries a supplementary bar, a², arranged on the inner side of the box E, and to these bars a² are hung the opposite ends of a rod, e, to which are pivoted arms e', carrying at their outer ends a bar, e², the latter being provided with a row of projecting fingers, i, each of which has, near the end, an open-

ing, to which, under the circumstances described hereinafter, is adapted a pin, m, on a frame, F, the latter being carried by sleeves n', adapted to vertical pins n on the bar e², and having pins which are embraced by the forked ends of arms M, secured to and projecting from the rod e. One of the arms is continued beyond the rod e, so as to form a lever, n², provided at its end with a pin, which, during the forward movement of the bars a a², rod e, and frame F, bears upon the under side of a rib, g, on a plate, G, but during the rearward movement bears upon the upper side of said rib.

The bar e² is connected to the lower ends of rods f, pendent from the front ends of rods J, which are guided in suitable lugs on the boxes E, so as to move on an angle, movement being imparted to the rods J from the rear ends of the bars a, to which said rods J are loosely connected.

Some of the warp-threads x are raised higher than the other threads, y, as is usual in weaving piled fabrics.

In the operation of the loom it is desirable to move the lay at intervals without operating the bars a, as described hereinafter; and in order to do this the hooks c on the lay are moved laterally until they are out of line with the spring-pins a' on the bars a. This operation of the hooks is effected by the adjustment of a forked plate, s, hung to the breast-beam, and acting on a pin, p, on the slide q, carrying the hooks. (See Fig. 4.)

The operation of the fork at the proper intervals is effected by a cam, t, on the shaft t', through the medium of the arrangement of rods and levers, clearly shown in Figs. 1, 2, 3, and 4.

The cam t acts on a pivoted arm, 2, the outer end of which is depressed by a spring, 3, so as to keep the arm always in contact with the cam.

The arm 2 is connected to a vertical bar, 4, the upper end of which is attached to an arm, 5, on a rock-shaft, 6, another arm, 7, on which is connected to one end of a rod, 8, the opposite end of which is jointed to the forked plate s. The lower end of the bar 4 is connected to one arm of a lever, 9, pivoted to the frame of the loom, as shown in Fig. 3.

The result of the operation of the loom will be understood on reference to Figs. 7, 8, 9, and 10.

As the bar e^2 and its fingers i are moved forward the fingers are thrust into the raised threads x of the warp, as shown in Fig. 7, and at the forward end of the movement a lateral throw is imparted to the bars a , and consequently to the bar e^2 and the fingers i , the latter being thereby thrust laterally under the threads x , which then lie over the fingers, as shown in Fig. 8. While these operations were being performed the front end of the lever n^2 and the frame F, carrying the pins m , were elevated; but when the fingers i are moved to the position Fig. 8, the pin at the rear end of the lever n^2 will have reached the front end of the rib g on the plate G, and will rise, thus allowing the pins m to descend and enter the openings in the fingers i , so as to firmly retain on said fingers the threads which they have caught. The fingers now commence the return movement, first moving laterally, as shown in Fig. 9, and then longitudinally until they reach the position shown in Figs. 1 and 10, the front ends of the fingers being then somewhat in the rear of and above the front edge of the woven fabric z , so that the warps x , which the fingers carry, form loops.

While these operations are being performed the plate s has been shifted, so that when the parts reach the position shown in Fig. 1 the slide q has been moved to such an extent as to free the spring-pins a' of the bars a from the control of the hooks c on the lay, and several picks are woven plain before the loops are released and the parts again thrown into gear prior to the formation of another set of loops in the same manner.

The object of weaving several picks plain between the rows of loops is to firmly bind the latter and prevent them from being pulled out.

A pivoted tappet, w , Figs. 6, 11, 12, and 13, operated by a rod, 10, from the lever 9, Fig. 3, is employed in order to effect the movement of the pin at the rear end of the lever n^2 from the upper to the lower portion of the rib g on the plate G, at the rear end of the same, the pin rising automatically from the lower to the upper portion of the said rib at the front end of the plate, owing to the preponderance of weight at the front end of the lever n^2 .

The fingers i and pins m may be duplicated on the under side of the shed, if desired, in

order to form loops on both sides of the fabric.

I claim as my invention—

1. The combination of the bar e^2 , having fingers i , the frame F, having pins m , and devices for supporting and operating the said bar and frame, so as to cause the fingers and pins to catch and release the threads, all substantially as set forth.

2. The combination of the bars a , the lay B, devices whereby the lay is caused to operate the bars, the bar e^2 , having fingers i , devices for connecting said bars a and e^2 , the connecting-rods f , the rods J, and means for supporting and guiding said bars a and rods J, as set forth.

3. The combination of the breast-beam A, the boxes E, the bars a , the supplementary bars a^2 , the rod e , the fingers e' , and the bar e^2 , carrying fingers i , as set forth.

4. The combination of the bars a , provided with pins b , the bar e^2 , having fingers i , devices for connecting said bar e^2 to the bars a , the boxes E, provided with plates d , having slots inclined at the front ends, the breast-beam A, and mechanism for longitudinally reciprocating said bars a , as set forth.

5. The combination of the bar e^2 , having pins n and fingers i , the frame F having pins m and sleeves n' , the forked arms M, and devices for operating the same, as specified.

6. The combination of the lay B, having a slide, q , carrying hooks c , the bars a , having pins a' , the forked plate s , for shifting the hooks, and devices for operating said plate and the lay, all substantially as described.

7. The combination of the breast-beam A, the boxes E, the bars a , the bar e^2 , carried thereby, and having fingers i , the frame F, having pins m , the lever n^2 , the plate G, having a rib, g , and devices for reciprocating the bars a , all substantially as set forth.

8. The combination of the plate G, having a rib, g , the frame F, means for supporting said plate and frame, the lever n^2 , the tappet w , and devices for operating the tappet and reciprocating the frame, as described.

In witness whereof I have signed my name to this specification in the presence of two subscribing witnesses.

JAS. C. ELLISON.
